(57) **CLAIM**

The ornamental design for a fitness device as shown and described.

DESCRIPTION

FIG. 1 is a front, left and bottom perspective view of a fitness device showing my new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is an enlarged view of encircled portion 8 of FIG. 1;

FIG. 9 is an enlarged view of encircled portion 9 of FIG. 1; and,

FIG. 10 is an enlarged view of encircled portion 10 of FIG. 1.

The broken lines which depict portions of the fitness device form no part of the claimed design. The broken lines which represent boundaries of the enlarged views form no part of the claimed design.

1 Claim, 10 Drawing Sheets
